UNITED STATES PATENT OFFICE.

HARDY BUSH, SR., OF NEWARK, NEW JERSEY.

DESIGN FOR A BRACELET.

Application filed October 11, 1924. Serial No. 11,030. Term of patent 14 years.

To all whom it may concern:

Be it known that I, HARDY BUSH, Sr., a citizen of the United States, and a resident of Newark, county of Essex, and State of New Jersey, have invented a new, original, and ornamental Design for Bracelets, of which the following is a specification, reference being had to the accompanying drawing, forming part thereof.

I claim:
The ornamental design for a bracelet, as shown.
